WALTER J. STEWART, OF JENNIE, ARKANSAS, ASSIGNOR OF ONE-HALF TO J. M. JONES
AND A. D. DUNN, BOTH OF JENNIE, ARKANSAS.

HAT-PIN.

1,184,590.

Specification of Letters Patent. Patented May 23, 1916.

Application filed October 2, 1915. Serial No. 53,813.

To all whom it may concern:

Be it known that I, WALTER J. STEWART, a citizen of the United States, residing at Jennie, in the county of Chicot and State 5 of Arkansas, have invented new and useful Improvements in Hat-Pins, of which the following is a specification.

This invention relates to hat pins, scarf pins and the like, and it has for its object to 10 produce a device of the class described in which the point will not protrude in an objectionable and dangerous manner when the pin is being used in its customary manner.

15 A further object of the invention is to produce a pin having a pointed penetrating member movably connected therewith and adapted to be moved to an obstructing position when the pin is being used so as to 20 prevent the accidental withdrawal or loss of the pin.

25 A further object of the invention is to produce a pin possessing the aforesaid characteristics, the same being of simple and improved construction.

With these and other ends in view which will readily appear as the nature of the invention is better understood, the same consists in the improved construction and novel 30 arrangement and combination of parts which will be hereinafter fully described and particularly pointed out in the claim.

In the accompanying drawing has been 35 illustrated a simple and preferred form of the invention, it being, however, understood, that no limitation is necessarily made to the precise structural details therein exhibited, but that changes, alterations and modifications within the scope of the claim may be 40 resorted to when desired.

In the drawing, Figure 1 is a side elevation of a hat pin constructed in accordance with the invention. Fig. 2 is a side view of the pin as seen at right angles to Fig. 1. 45 Fig. 3 is a sectional view taken on the line 3—3 in Fig. 2. Fig. 4 is a view similar to Fig. 2, but showing the penetrating member disposed at right angles to the shank or body of the pin to prevent withdrawal 50 of the latter. Fig. 5 is a perspective detail view showing the shank and the penetrating member separated.

Corresponding parts in the several fig-

ures are denoted by like characters of reference.

The shank or body 15 of the improved pin has at one end thereof a longitudinal recess 16 to receive a tongue 17 extending from the point or penetrating member 18. The tongue 17 has a longitudinal slot 19 for 60 the passage of a fastening member, such as a rivet 20, extending transversely through the shank of the pin at the recessed end thereof. The tongue 17 has at its inner end a projecting lip or locking member 21 for 65 the accommodation of which a notch 22 is provided at the inner end of the recess 16.

It will be seen that when the parts are assembled, the slot 19 permits the penetrating member to be moved longitudinally to 70 enable the lip 21 to be engaged with the notch 22, thereby preventing the penetrating member from being moved or rotated about the axis of the rivet 20. By slightly retracting the penetrating member longitudinally with respect to the shank 15 it may be swung or moved to a position substantially at right angles to said shank, as will be seen in Fig. 4, thereby preventing 75 the withdrawal of the pin.

If desired, a small coiled spring 23 may be placed in the slot 19 between the inner end of said slot and the rivet 20 to exert an inward tension on the penetrating member, whereby the lip 21 will be retained in 85 engagement with the notch 22.

The contacting portions of the shank 15 and the penetrating member 18 are preferably rounded, as indicated at 24, for the double purpose of assisting in retaining the 90 parts in position with the penetrating member extending in alignment with the shank of the pin and also facilitating the operation of moving it to a position substantially at right angles to the shank.

Having thus described the invention, what is claimed as new, is:—

In a device of the class described, a shank having at one end a longitudinal recess provided with a notch at its inner end, a penetrating member having a tongue engaging said recess, said tongue being provided with a longitudinal slot and with a lip engaging the notch at the inner end of the recess, and a fastening member extending transversely 100 through the recessed end of the shank and 105

through the slotted tongue, the contacting portions of the shank and the penetrating member being rounded to present arcuate meeting faces; in combination with a spring fitted in the slot of the tongue between the fastening member and the inner end wall of the slot.

In testimony whereof I affix my signature in presence of two witnesses.

WALTER J. STEWART.
